UNITED STATES PATENT OFFICE.

ALBIN FRANZ BARTH, OF GROSSENHAIN, SAXONY, GERMANY.

SHIP'S PROPELLER.

SPECIFICATION forming part of Letters Patent No.317,438 dated May 12, 1885.

Application filed June 17, 1884. (No model.)

To all whom it may concern:

Be it known that I, ALBIN FRANZ BARTH, of Grossenhain, Kingdom of Saxony, Germany, have invented a new and useful Improvement in Ships' Propellers, of which the following is a specification.

My invention relates to a propeller adapted to act partly as an ordinary paddle-wheel and partly as a centrifugal pump, which draws in 10 water from the side and throws it by centrifugal force toward the circumference of the casing which incloses the propeller, the water being at the same time carried round by the blades of the propeller and delivered at the 15 bottom, like the water which leaves the paddles of an ordinary paddle-wheel.

In the accompanying drawings, Figure I is an axial section, and Fig. II a cross section of a propeller as applied to a flat-bottomed ship. Fig. III is an axial section, and Fig. IV 20 a cross-section of a propeller as applied to a ship with deep draft. Figs. V to X illustrate modifications.

In the construction illustrated by Figs. I 25 and II, a casing, g , open at the bottom, is formed in the lower part of the vessel and closed at the sides by partitions c . These partitions have axial openings d , which lead to the suction-chambers e , situated at the 30 sides of the casing g . The propeller inclosed in the casing g consists, chiefly, of a horizontal shaft, a , carrying blades b , which reach below the bottom of the vessel. Each suction-chamber e is curved at the top to the same radius 35 as the opening d , and diverges toward the bottom, where it has the same width as the opening of the casing g , as shown by dotted lines in Fig. II. To the open base of the casing g and suction-chambers e corresponds, 40 therefore, a single opening in the bottom of the vessel, through which the three chambers are accessible.

The propeller may be placed in the center of the ship's bottom, or in the front or back 45 part of the vessel. Two propellers may be placed at the sides of the vessel. Instead of allowing the partitions c to extend downward as far as the blades of the paddle-wheel, it may cease at the bottom of the vessel, so that 50 the paddle-wheel alone projects over the same.

In vessels of deep draft two propellers may be placed right and left of the keel, in the

manner illustrated by Figs. III and IV. The wheels b' may be mounted on the same shaft a' which reaches across the center line of the 55 ship, or on separate shafts. Instead of two suction-chambers there is only one, e' , situated at the outer side of the casing g and closed at the bottom, but admitting water at the top through the suction-pipe f' , which may have 60 a widened mouth in the hull of the ship.

A propeller of the same type as in Figs. I and II may be placed obliquely on each side of the vessel, as illustrated by Fig. V, which shows only one suction-chamber e ; but there 65 may be two such chambers, as in Fig. I, one on each side of the casing g^2 .

Fig. VI shows a propeller with horizontal axis, one suction-chamber e , and outer partition c extending down as far as the blades of the 70 wheel, while the inner partition reaches as far as the ship's bottom only.

Fig. VII shows a pair of propellers for a flat-bottomed vessel. A pair of wheels, b^4 , inclosed in casings g^4 , are mounted on the same shaft 75 a^4 , and have only one suction-chamber e^4 , situated between the casings g^4 .

Instead of constructing a separate suction-chamber, water may be sucked into the center of the casing g^5 directly by openings d^5 80 provided in the side of the ship c^5 , as shown by Figs. VII and IX, provided that the vessel has sufficient draft. In sailing-vessels my apparatus may be used as an auxiliary propeller. In this case the wheel has only three paddles, 85 as illustrated by Fig. X, which, when the propeller is out of action, are placed inside the casing g^6 , so as not to offer any resistance to the progress of the vessel.

The casing and the suction-chambers may 90 be composed in any convenient manner, which will readily suggest itself. For instance, each casing or chamber may be divided into an upper and a lower half, so that the bearings for the shaft are partly formed in the upper and 95 partly in the lower half of the partition.

The lower part of the partitions c may have any convenient shape, and the blades of the 100 wheels a may be rectangular, as in Fig. I, or they may be limited obliquely, as in Fig. III, or by a curve, as in Fig. VIII. The blades may be completely flat, as in Fig. II, or curved, as in Fig. IV, or of any other convenient shape.

Any suitable number of propellers may be used in the same ship, and the mouth of the suction-chamber or opening may be provided with gridirons or wire netting to prevent the intrusion of plants and other solid bodies.

What I claim is—

1. The combination of a paddle-wheel with a paddle-wheel chamber having a lateral opening for admitting water near the axis of the wheel, and allowing the lower part of the wheel to project so as to admit water freely at the front and at the back of the lower paddles, for the purpose of combining with the ordinary paddle-wheel action, the reaction resulting from the admission of water at the center and its discharge at the rear of the wheel, substantially as described.

2. The combination of a paddle-wheel with a paddle-wheel chamber, and a lateral suction-chamber communicating with the paddle-wheel chamber through an axial opening, the paddle-wheel projecting below the wheel-chamber so as to allow free access of water to the front and to the back of the lower paddles, substantially as and for the purpose described.

In testimony whereof I have signed my name to this specification in the presence of two subscribing witnesses.

ALBIN FRANZ BARTH.
